MACHINE FOR SETTLING AND COMPACT-
ING FLOUR IN BAGSHelmer Anderson, Minneapolis, Minn., assignor to
General Mills, Inc., a corporation of Delaware

Application July 14, 1939, Serial No. 284,423

3 Claims. (Cl. 259—72)

This invention relates to a machine for use in the milling industry which will improve the packaging of any kind of granular material, but more especially flour in containers or paper bags by 5 providing a table for supporting said bags and means for reciprocating and agitating said table obliquely forwardly upward and downwardly backward in a horizontal position for settling and compacting said material by jogging in said bags 10 with most of its entrained air removed therefrom prior to closing the open end thereof.

The machines that are now being used receive bags filled with flour on a continuous moving 15 vibrating or non-vibrating belt which feed the bags forwardly thereon during the moving cycle against stationary protruding obstructions that engage the side walls of the bags for the purpose of indenting the same, thereby displacing and agitating the material therein, or as used on other 20 machines, said moving belt is only a primary feed conveyor placed ahead of a vibrating flat receiving panel which only joggles thereon vertically up and down the bags filled with flour, the forward progress of said bags is accomplished only by the 25 moving of a continuous line of bags on the primary moving conveyor, these moving bags are the only means used to cause the bags on the vibrating panel to move forwardly. It can be readily understood that the forward progress of the bags 30 on the vibrating panel stops when the primary conveyor is empty, and the bags which are then left on said panel move only vertically up and down.

A principal object of my invention is to provide 35 a machine for settling and compacting flour in a single bag, or a plurality of bags in which there is a rigid self sustaining frame member having assembled therewith supporting means and movable means which operate with suitable velocity 40 for reciprocating laterally of said frame obliquely forwardly upward and downwardly backward in a horizontal position a bag carrying table, said table having thereon adjustable vertical supporting members for retaining one or more paper 45 bags filled with a predetermined amount of flour in a vertical position while they are being moved individually by said table movement in a forward jogging like manner along the table face, during which cycle the flour is caused to settle and compact in the bag with the entrained air being removed therefrom, thus providing at the end of 50 said cycle a bag filled with flour having suitable dimensional form and size with its contents so firmly compacted that further settling of the flour 55 is substantially eliminated.

A further and highly important object of my invention is to provide a machine for settling and compacting flour in a bag or bags, whereby the reciprocating oblique forward-backward movement of the bag-carrying table can differentiate 5 from the reciprocating forward movement of the bags filled with flour along the table in order to provide a jogging forward motion to the said bags upon the table face, said jogging motion of the bags being caused by the abutting force 10 contact between the bag bottom and table face, due to the table being moved down faster than the bag can drop down from its upper level during the backward reciprocating stroke, thus leaving the bag momentarily freely suspended before 15 it is abuttingly engaged by force with the table face on each of its forward reciprocating strokes.

Another object of my invention is to provide a machine for settling and compacting flour in a bag whereby some of the means attached thereto 20 can be replaced or varied in design for the purpose of changing the limits of the oblique forward-backward movement and the reciprocating movement of the flour bag-carrying table, each of the means operating in combination with each 25 other to cause said table to move a bag filled with flour vertically thereon in a forward reciprocating jogging manner.

A further object of my invention is to provide a 30 machine for settling and compacting flour in a bag, having means that operate in combination with a bag-carrying table for the purpose of maintaining said table in a level horizontal position during the reciprocating oblique forward-backward movement of said table.

It is a further object of my invention in combination with a machine for settling and compacting flour in a bag, to provide a bag-carrying table having extending perpendicular from its bag supporting face, adjustable side walls which 40 retain the bags in an upright vertical position in an interior passageway between said walls during the reciprocating forward movement of the bags filled with a predetermined amount of flour on said table.

It is a further object of my invention to have in combination with a machine for settling and compacting flour in a bag, means in combination with said machine for driving a bag feed conveyor which is suitably supported, and in abutted alignment relation at the receiving end of said settling and compacting machine, to provide carrying means for supplying bags filled with a predetermined amount of flour from said conveyor to an obliquely reciprocating forward and back- 50 55 55

ward moving table on the flour compacting and settling machine.

These and other objects and advantages of the invention will become more readily apparent when considered with the following description and accompanying drawings, but it is to be understood that various changes may be made within the scope of the claims which follow.

The invention is fully illustrated in the accompanying drawings forming a part of this specification, wherein:

Figure 1 is a side elevational view of the entire machine with the bag feed conveyor unit attached to the unit for settling and compacting flour in a bag with parts of the conveyor structure broken away.

Figure 2 is a longitudinal vertical sectional view thru the unit for settling and compacting flour in a bag and part of the feed conveyor, showing in full and dotted lines a plurality of bags filled with flour on the bag-carrying table and the feed conveyor.

Figure 3 is a horizontal plan sectional view taken on the line 3—3 of Fig. 1 showing the driving mechanism for the bag-carrying table and the detail construction of the feed conveyor with the feed belt removed therefrom.

Figure 4 is a horizontal plan sectional view taken on the line 4—4 of Fig. 1, showing the detail construction of the machine frame used in the unit for settling and compacting flour in a bag with further details of the driving mechanism.

Figure 5 is a vertical transverse sectional view across the front of the unit for settling and compacting flour in a bag, taken on the line 5—5 of Fig. 2 showing a bag filled with flour in a vertical position between the vertical side walls on the flour bag-carrying table.

Figure 6 is a fragmentary vertical transverse sectional view taken on the line 6—6 of Fig. 2 showing the reciprocating mechanism used in combination with the flour bag-carrying table.

Figure 7 is a fragmentary vertical transverse sectional view on the line 7—7 of Fig. 2 showing an end view of some of the driving means and its supporting frames.

Figure 8 is a fragmentary plan view of the feed conveyor and the front portion of the flour settling and compacting unit, showing the adjustable means used in combination with the vertical side wall used for supporting in a vertical position the bags filled with a predetermined amount of flour.

Figure 9 is a longitudinal vertical sectional view of part of the entire machine similar to Fig. 1, but showing a modified form of mechanism used for the purpose of maintaining the flour bag-carrying table in a level horizontal position.

Figure 10 is a rear view of Figure 9 as seen from the rear of the machine on the line 10—10 of Figure 9.

Referring to the drawings the entire assembled apparatus consists of two units which will be referred to by numerals 10 and 12. The machine 10, provides means for settling and compacting the flour F, contained in a bag or bags, and has mounted therein a flour bag-carrying table 11, that is obliquely reciprocated forwardly upward and downwardly backward in a horizontal position, said table 11, receiving either direct from an operator or from the bag feed conveyor unit 12, the containers or bags B, which are filled with flour F, by a bag filling machine. I have shown in the drawings the two units 10 and 12, as-

sembled together for use in combination with each other and will describe them as shown.

The frame structure of the machine 10, is constructed of suitable material to withstand the continuous reciprocating action of the various machine parts during the moving and joggling of the bag or bags on the table 11. The frame structure as shown in Figures 1, 2, 3 and 7, comprises a pair of vertical reinforced right and left hand side frame members 13 and 14, which are united together by means of transverse cross bars 16, 17 and 18, the bearing brackets 20 and 21, and the adjustable motor support 22, by means of bolts 23, to form a rigid self sustaining frame member for supporting the driving and driven parts which are enclosed within its structure.

The means for driving the various machine parts consist of an electric motor 24, supported by means of bolts 25, to the adjustable motor support 22, and has extending therefrom a shaft 26, that has fastened thereto at its outer extremity a flexible coupling 27, having an extension shaft 28, keyed thereto. The shaft 28, has also keyed thereto at its other end a flexible coupling 29, which drives by means of shaft 30, a reduction gearing unit 31, that drives by means of the sprocket wheel 32, chain 33, the sprocket wheel 34, and the shaft 35, which has keyed thereto the driving pulley 36, of the feed conveyor 12, that will be described in detail later.

Interposed between the coupling 27, and the motor 24, are pulleys 40, that are keyed to the motor shaft 26, for the purpose of driving the eccentric shaft 41, by means of the belts 42 and the pulleys 43. The shaft 41, having secured thereto at 44, the self aligning ball bearings 45, which are supported in dustproof oil sealed housings 46, of the brackets 20 and 21. Referring to Figures 2, 5, 6 and 7, it can be readily seen that the entire working load of the machine is carried by said bearings 45, thus I have found it desirable to key on the shaft 41 at 47, a fly wheel 48, so that the speed of said shaft will not fluctuate while the machine is operating. The shaft 41 extends beyond the bearing brackets 20 and 21, and has integral therewith reduced cylindrical extensions 49 and 50, whose center lines are in alinement with each other but are not in alinement with the center line of the main portion of shaft 41, which is supported in the bearings 45. The purpose of this construction is to have on shaft 41, at 49 and 50, a pair of eccentric extensions that support at 51 and 52, self aligning ball bearings 53 and 54.

The rotating of shaft 41, will impart by means of the eccentrics 49 and 50, a reciprocating movement to the outer rings of the bearings 53 and 54, which are encased in the adjustable pitmans or connecting rods 55. These connecting rods 55, have a resilient universal ball and socket connection 56, in depending members 57, on the bottom surface of the bag-carrying plate 11, adjacent its ends which in combination with the eccentrics 49 and 50, on rotating shaft 41, operate said plate in a reciprocating vertical direction, but other means working in combination therewith cause the plate 11, to move in a forward-upward oblique direction during the upstroke of the eccentrics, and in a downward-backward direction during the downstroke of the eccentrics while other means retain said plate 11, in a horizontal level position during its reciprocating oblique forward and backward movement. I have shown in Figures 2, 5 and 6, elevational and sectional views of the table 11, and the various means for

operating and guiding it during the oblique reciprocating forward-backward movement with the bags B filled with a predetermined amount of flour assembled thereon.

5 Extending vertically from the face surface of plate 11, on its right and left hand edges, diametrically opposite each other, adjacent the front and rear extremities of said plate and integral therewith, are roller supports 58 and 59, having extending outwardly therefrom bearing pins 60, for rotatably retaining thereon a cylindrical roller 61. Each roller extends into an elongated oblique aperture 62, within individual guide plates 63, that are retained by means of bolts 64, to the upright members 65 and 66, on the right and left hand corners of the frame members 13 and 14. The apertures 62, as shown in Figures 1 and 9 do not extend vertically within the plates 63, relatively to the face surface of plate 11, but extend upwardly and forwardly in an oblique line for the purpose of causing the plate 11 to reciprocate in a forward and backward direction when operated by the pitmans or connecting rods 55, and the eccentrics 49 and 50, on shaft 41. It can be readily understood that the limits of the oblique forward-upward and downward-backward travel of plate 11, will be regulated by the inclined angle of the aperture in the plates 63, with the limits of the reciprocating travel regulated by the lift of the eccentrics, thus regulating the bag joggling period or the time required for the bag B to travel the complete length of the table 11, in order to completely settle and compact the flour in the bag.

For retaining the plate 11, in a horizontal plane during the movement of the connecting rods 55, and to prevent sideward movement of said plate and its connecting rod connections during the moving and joggling of the bag on said plate, I have provided a pair of guide brackets 67 and 68, which are pivotally mounted on shoulder bolts 69, in hubs 70, integral with extensions 71 and 72, on the frame members 13 and 14. These guide brackets 67 and 68, consists of a pair of extending arms 73 and 74, connected together by a transverse arm 75, to form a rigid bracket member for receiving at their outer extremities in bearing hubs 76, extending pins 77, of brackets 50 78 and 79, which extend downwardly from the lower surface of plate 11, proximate to the right and left of connections 56 and 57. This construction is shown in Figure 1 thru Figure 8, it being necessary to assemble the brackets 67 and 68, at an angle with reference to the oblique angle of the aperture 62, so that the center line of the arms 73 and 74, extending thru the pins 69 and 77, will be at right angle to the center line extending thru the pins 77 of the oblique aperture 62. The aperture 62, must also be made wide enough to prevent binding action of the rollers 61, within the apertures when the plate 11, is reciprocating, due to the circular movement of the brackets 67 and 68, about the shoulder bolts 69.

In Figures 9 and 10, I have provided another form of construction for maintaining the plate 11, and its cooperating parts in the positions just referred to, it being understood that like reference numerals will be used in these figures where corresponding details are used. The brackets 67 and 68, are replaced by the guiding links 80, 81, 82 and 83 while the brackets 78 and 79, are replaced by projections 84, which are integral with the bottom of the plate 11. The

links 80 and 82, are pivoted on shafts 85, at their lower extremities to frame extensions 86, and have pivotally mounted thereto at their upper extremities 87, links 81 and 83, said links being pivotally connected to projections 84, by means of the shafts 88. The links 81 and 83 are each made in integral pairs while the links 80 and 82 are in unattached pairs. This linkage connection between the frames and plate 11, provides a means whereby sets of plates 63, having various oblique apertures 62 therein may be interchanged to provide different angles of the slot to give different forward speeds without replacing the link connection as would be the case in the guide bracket construction 67 and 68, shown in Figures 1 thru 8. In this linkage connection of Figures 9 and 10, the links or arms 80 and 82, rotate about their axis 85, in a forward and backward direction while the arms 81 and 83, will rotate up and down about their axis 87, each set of arms working in combination with each other and in synchronism with the reciprocating forward-backward movement of plate 11. This linkage mechanism provides the means for counteracting any angular changes in the apertures 62, without replacing or changing any of its parts, thus the speed of the forward progress of the bags filled with flour F, along the surface of table 11, can be readily changed by the replacement of the plates 63.

The bags B, are retained in a vertical position on the plate 11, by means of the adjustable vertical projecting side members 89, as best shown in Figures 1, 2, 5 and 8. Said members 89, are designed as shown in Figure 5, to engage the said contour of the bags when filled with flour F, and are retained on plate 11, by means of cap screws 90, in the elongated apertures 91, which are the adjusting means for positioning said side members 89, to fit the contour of the different sizes of bags that are now used for retaining various weights of flour F.

In Figures 1 and 7, on the lower reinforcing section of frame 13, and attached thereto by means of bolts 92, is a bearing bracket 93, supporting a shaft 94, having a bell crank idler pulley bracket 95, assembled thereon for tensioning the driving belts 42, by means of the idler pulley 96, and the tensioning spring 97. The arms 98, of bracket 95, have rotatably interposed thereon said pulley 96, which engages the belt 42, and tensions same by means of said spring 97, which is anchored at one end to the frame 13, at 99, its other end being attached at 100, to arm 101, of the bracket 95.

The unit 10, having been described as a mechanism for compacting and settling flour F, in a bag, as has already been referred to, a bag feed conveyor 12, is secured thereto in alignment with table 11. The shaft 35, is journaled in bearings 102, which are retained within bearing retainer extensions 103, on frame members 13 and 14. Said extensions support in combination with the cap screws 104, the rear portion of the longitudinal side members 105 and 106, which together with the integral transverse tie bars 107, form the conveyor frame 108, the front of which is supported by means of the standards 107, in the adjustable supports 108, secured to the side members 105, and 106. Adjacent the rear supports 108, and integral with members 105 and 106, are bearings 109, for receiving the driven shaft 110, and its attached pulley 112. Said shaft and pulley being driven by the endless conveyor belt 113, which is driven by the driving pulley 36, 75

and the sprocket wheel or pulley 34, heretofore referred to. The belt 113, as best illustrated in Figures 1 and 2 consists of an endless belt extending from the periphery of pulley 112, thence over the face surface of plate 114, and then around half of the periphery of pulley 38, where it then returns back to its engagement with, and from the periphery of pulley 112. The plate 114, is supported on frame 108, by means of countersunk head screws 126, in the cross bars 107, for supporting the bags filled with flour F, when fed along said conveyor belt to the table 11. The conveyor belt 113, is tensioned by the idler pulley 115, said pulley being rotatable on shaft 118, in the idler supporting bracket 117, which is freely mounted on shaft 118, in hubs 119, on frame member 108, its tensioning position is regulated by means of the cap screws 120, in the arms of bracket 117, and the apertures 121, in the members 105 and 106. The side member 106, has secured thereto by means of cap screws 122, a vertical longitudinal skeleton frame member 123, for guiding the bags on the conveyor belt 113, so that said belt can move them onto the plate 11, said member 123, is assisted by an angular shaped adjustable guide member 124, on plate 114, which is adjusted by means of the cap screws 125, in the plate 114, and the apertures 126, in the base flange of member 124, said flange being raised to clear the conveyor belt when projecting over the face surface of said belt.

Located independently at the discharge end of table 11, is a conveyor 130, that may be used for carrying the bags of flour F, away from the machine 10, after they have been subjected to the reciprocating forward movement on table 11.

Operation

The machine in combination as herein disclosed may be interposed between a bag filling machine and a bag top closing machine so that the bags can be delivered either directly onto the conveyor belt 113, or upon the table 11, of the settling and compacting machine, from the bag filling machine, or from some other source of supply. When the bags are placed onto the conveyor belt 113, they move with said belt in a vertical upright position between the members 123, and 124, onto the obliquely reciprocating forward-backward moving plate 11, of the settling and compacting machine 10, thru the interior passageway 131, formed by the vertical guide members 89, onto the conveyor 130, or they may be manually removed at this point from plate 11. The conveyor 113, serves only as a means for delivering the bags filled with flour F, to the settling and compacting machine while the conveyor 130, serves only as a means for delivering them to some other machine or place.

The bags filled with flour F, when delivered to the table 11, are subjected to a reciprocating for-

ward joggling movement across the table caused by the contacting engagement between the table and the bag filled with flour F. The table is caused to move in a horizontal position obliquely forwardly upward and obliquely downwardly backward in a reciprocating motion at the desired speed or velocity so that the bags thereon will be joggled along in a forward direction on said table, during said joggling movement the flour F, in the bags will be so firmly compacted that further settling of the flour F, is practically eliminated, thus preparing said bags of flour F, for the bag top closing operation.

Having thus described my invention, what I claim is:

1. In apparatus for settling and compacting flour in bags, a horizontally disposed table, means for supporting and guiding said table to permit the table to move only obliquely upwardly and forwardly or downwardly and backwardly with a parallel motion, and means including a link having a universal connection at one end with the table and an actuating crank for the link which moves in a plane at a right angle to the plane of movement of the table for thus rapidly reciprocating said table up and down in said supporting and guiding means to advance bags along said table as the material therein is settled and compacted.

2. In apparatus for settling and compacting flour in bags, a horizontally disposed table, means for supporting and guiding said table to permit the table to move only obliquely upwardly and forwardly or downwardly and backwardly with a parallel motion, a shaft journalled beneath the table and extending longitudinally thereof, and eccentrics carried by said shaft and having universal joints at their ends connected to the bottom of the table for rapidly reciprocating said table up and down in said supporting and guiding means to advance bags along said table as the material therein is settled and compacted.

3. In apparatus for settling and compacting flour in bags, a horizontally disposed table, a supporting frame, linkage means connecting the forward and rear portions of said table to said frame for keeping the table horizontal, reciprocable means on said frame adjacent each linkage and universally connected to said table for rapidly vibrating the table up and down, guide plates secured alongside the table and having oblique apertures extending upwardly and forwardly, and pins carried by said table movable in said apertures to cause the table to be moved upwardly-forwardly and downwardly-backwardly when vibrated by said vibrating means to settle and compact flour in bags and to advance the bags along the table at a rate determined by the angle of obliquity of the apertures.

HELMER ANDERSON.
